(57) **CLAIM**

The ornamental design for an apparel pattern as shown and described.

DESCRIPTION

FIG. 1 is a view of an apparel pattern showing the new design; and,

FIG. 2 is a view of the apparel pattern shown on a bra. The evenly broken lines (dash-dash lines) shown in the Figures are only for illustrative purposes to show visible environmental structure and form no part of the claimed invention.

The boundary lines (as opposed to the evenly broken lines) shown in various ones of the Figures in dash-dot-dash form do not exist in reality in the respective article embodying the design and are only for illustrative purposes to show bounds of the claimed design. It is understood that the claimed design extends to the boundary but does not include the boundary.

The dot broken lines depict portions of the apparel pattern that form no part of the claimed design.
